US00D925478S

(12) **United States Design Patent** (10) **Patent No.:** **US D925,478 S**
(45) **Date of Patent:** ** *Jul. 20, 2021

(54) **CONTROL DEVICE**

(71) Applicant: **Lutron Technology Company LLC**,
Coopersburg, PA (US)

(72) Inventors: **Chris Dimberg**, Easton, PA (US);
Susan Hakkarainen, Doylestown, PA
(US); **Jason C. Killo**, Emmaus, PA
(US); **Brad Michael Kreschollek**,
Bethlehem, PA (US); **Noel Mayo**,
Philadelphia, PA (US); **Matthew Philip
McDonald**, Phoenixville, PA (US)

(73) Assignee: **Lutron Technology Company LLC**,
Coopersburg, PA (US)

(*) Notice: This patent is subject to a terminal disclaimer.

(**) Term: **15 Years**

(21) Appl. No.: **29/723,734**

(22) Filed: **Feb. 10, 2020**

Related U.S. Application Data

(63) Continuation of application No. 29/669,956, filed on Nov. 13, 2018, now Pat. No. Des. 878,310, which is a continuation of application No. 29/629,790, filed on Dec. 15, 2017, now Pat. No. Des. 839,847, which is a continuation of application No. 29/566,966, filed on Jun. 3, 2016, now Pat. No. Des. 808,912.

(57) **CLAIM**

The ornamental design for a control device, as shown and described.

DESCRIPTION

FIG. 1 is a front perspective view of control device showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

1 Claim, 4 Drawing Sheets
